SIDE RAILING MOUNT

Sherman J. Shore, Pittsburgh, Pa., assignor to Napco, Inc.,
Pittsburgh, Pa., a corporation of Pennsylvania

Filed Apr. 5, 1968, Ser. No. 11,313

Term of patent 14 years

Int. Cl. D8—03

U.S. Cl. D54—1

FIG. 1.

FIG. 2.

FIG. 3.

FIG. 4.

FIG. 5.

FIG. 7.

FIG. 6.

FIG. 1 is a perspective view of a side railing mount embodying my design;

FIG. 2 is a rear elevational view thereof;

FIG. 3 is a front elevational view thereof;

FIG. 4 is a side elevational view looking from the left of FIG. 2;

FIG. 5 is an elevational view of the opposite side from that shown in FIG. 4;

FIG. 6 is a bottom view; and

FIG. 7 is a top plan view.

The broken lines are for illustrative purposes only.

I claim:

The ornamental design for a side railing mount, substantially as shown and described.
